UNITED STATES PATENT OFFICE.

JAY BROWNLEE DAVIDSON AND EDGAR V. COLLINS, OF AMES, IOWA, AND DARRELL B. LUCAS, OF NEW BRUNSWICK, NEW JERSEY, ASSIGNEES TO IOWA STATE COLLEGE OF AGRICULTURE AND MECHANIC ARTS, OF AMES, IOWA, A CORPORATION OF IOWA.

AUTOMATIC PLOW.

Application filed June 16, 1924. Serial No. 720,360.

The object of our invention is to provide a motor driven plow device of simple, durable and inexpensive construction for automatically performing all of the various operations required in plowing successive furrows across a field.

More specifically it is our object to provide improved means for automatically maintaining a motor driven plow in position to follow the land side of a previously made furrow.

A further object is to provide improved means for reversing the movement of the plow when it approaches a fence or other obstruction at the end of the field.

A further object is to provide means for automatically moving the device laterally at the end of the field and after the engine has been reversed, to thereby cause the furrow wheel to move from the furrow, in which it originally traveled, to the furrow last made during the progress of the plow across the field.

A further object is to provide improved means for automatically stopping the driving means or engine in the event that the furrow wheel should move out of the furrow to a predetermined extent.

A further object is to provide means for automatically stopping the motor when the plow comes adjacent to a side fence or other obstruction provided for that purpose.

Our invention consists in the construction, arrangement and combination of the various parts of the device, whereby the objects contemplated are attained, as hereinafter more fully set forth, pointed out in our claims, and illustrated in the accompanying drawings, in which:

Figure 1 shows a side elevation of a device embodying our invention, with one of the plows in a furrow and the reversing mechanism in engagement with a fence.

Figure 2 shows a side elevation of same with the reversing mechanism partly tripped to reverse the engine.

Figure 3 shows a similar view with the reversing mechanism moved to position for reversing, and one of the plows elevated above the ground. The arrow indicates the direction of movement of the plow beam and the driving wheels.

Figure 4 shows a similar view showing a further progress of the reversing movement

and also illustrating the relative positions of the supporting wheels for causing the plow to move laterally into an adjacent furrow.

Figure 5 shows a similar view with the movement nearly completed with one of the plows commencing a new furrow, and the supporting wheels in position to enter the last previously formed furrow.

Figure 6 shows an end elevation of the device in position for use, one of the plows being removed and the beam shown in section. In this figure the position of the supporting wheels, when both are traveling on level ground or out of the furrow, is indicated by dotted lines, as is also the position of the device for cutting off the spark plug circuit when the furrow wheel is out of the furrow, taken on the line 6—6 of Figure 9.

Figure 7 shows an enlarged, detail, sectional view of the driving wheels and axle and connected parts.

Figure 8 shows an enlarged, detail, side view illustrating the means for automatically breaking the spark circuit when the furrow wheel is out of a furrow.

Figure 9 shows a top or plan view of the complete device. The dotted lines show the manner in which the plow moves from one furrow in a transverse direction toward the furrow last made when reversed at the end of the field; and

Figure 10 shows an enlarged, detail, sectional view on the line 10—10 of Figure 9.

Referring to the accompanying drawings, we have used the reference numeral 10 to indicate the driving axle. Keyed to one end of the axle is a supporting and driving wheel 11, and rotatably mounted on the other end of the axle is a supporting and driving wheel 12. The outer end of the hub of the wheel 12 is formed with a segmental notch 13 with shoulders 14 at the opposite ends of the notch, and keyed to the axle 10 is a lug 15 normally resting in said notch, and designed to engage said shoulders when the lug is at opposite limits of its movement within the notch.

Fixed to the driving wheel 12 is a large gear wheel 16 in mesh with a small gear pinion 17. This gear pinion 17 is fixed to a shaft 18 on which there is rotatably mounted two beveled pinions 19 and 20 in mesh with a third beveled pinion 21, and slidingly but non-rotatably mounted on the

shaft 18 between the beveled pinions is a clutch member 22 designed to engage with a coacting clutch member 23 on each of the beveled pinions 19 and 20. This sliding clutch member is connected to a bell crank lever 24 which is operatively connected to a rod 25 by which its movement may be controlled.

The engine proper, which is preferably of the internal combustion type, is indicated generally by the reference numeral 26, and of itself forms no part of our present invention. It is provided with a driven shaft 27 having a sprocket wheel 28 thereon and connected by the sprocket chain 29 with a sprocket wheel 30 on a shaft 31, and this shaft 31 is fixed to the beveled pinion 21, so that during the operation of the engine, the beveled pinion 21 is constantly rotated in one direction, and the direction of travel of the pinion 17 may be reversed by the manipulation of the rod 25. The engine and gear devices referred to are mounted upon a suitable frame 32 fixed upon the bearings 33 which are carried by the main axle 10.

Secured to the main frame 32 are two downwardly extended lugs 34, and between these lugs there is pivotally mounted the plow beam 35. A brace 36 is connected to opposite portions of the beam 35 and to the top of the engine proper. Mounted on opposite ends of the plow beam 35 are the two plows 37, the points of which extend toward each other.

For manipulating the rod 25 we have pivoted to one end of the beam 35 a bell crank lever 38, one arm of which lever is pivoted to the rod 25. The other arm of the lever 38 is connected to a contractile coil spring 39, the other end of which spring is connected to the beam 35. These parts are so arranged that when the bell crank lever 38 is in one position of its movement, as shown at the left in Figure 1, the spring will tend to hold it in that position, and when it is moved to the opposite limit of its movement, the spring will pass the pivotal center of the bell crank lever 38 and tend to hold it in its adjusted position.

Mounted upon the opposite end of the beam 35 is a link 40, and pivotally connected to the bell crank lever 38 and the link 40 is a trip arm 41, which trip arm is extended beyond the plows and preferably has a downwardly extended portion 42 at each end designed to engage the wires or rails of a fence 43.

The operation of this part of the device is as follows:

Assuming that the engine is operated and the driving wheels are moved in a direction toward the fence 43, as shown in Figure 1, then when the trip arm 41 engages the fence, it will be held stationary while the plow advances. This will operate the bell crank

lever 38 to overcome the tension of the spring 39 and throw the lever past center so that the spring 39 will yieldingly hold it in such position past center, and this movement of the lever 38 will operate the rod 25 to reverse the movement of the pinion 17 through the three beveled gears 19, 20 and 21 and the clutch device interposed between them.

The arrangement of the driving wheels 11 and 12 on the shaft 10 and the function of the lug 15 is as follows:

During the normal operation of the machine across the field and when the driving wheel 12 is in a furrow, one of the shoulders 14 will engage the lug 15 and drive the shaft 10 and the driving wheel 11 through the engagement of this shoulder 14 with the lug 15, and due to this arrangement the driving wheel 12 will advance across the field slightly in advance of the driving wheel 11, as shown in Figure 2. Then when the movement of the engine is reversed, the driving wheel 12 is free to move a certain predetermined distance before any motion is imparted to the driving wheel 11, and on this account the driving wheel 12 will move a considerable distance in advance of the driving wheel 11, and this will result in causing the plow device to move transversely, as indicated by the dotted lines in Figure 9. However, this advance movement will only continue for a short time, or until the drive lug 15 engages the opposite shoulder 14, as shown in Figure 6, and until the driving wheel 12 engages the land side of the furrow last made. In this connection, the dotted lines in Figure 9 show the drive wheel 12 in its position just before engaging the land side of said furrow, and when in this position, both the wheels 11 and 12 will be positively driven by the engine and the land side of the furrow will offer sufficient resistance so that the plow will straighten out and run parallel with the furrow with the wheel 12 slightly in advance of the wheel 11, tending to guide the progress of the plow across the field in a straight line, using the land side of the furrow as the means for keeping it from moving laterally in a direction toward the land side. The fact that the wheel 12 is slightly in advance of the wheel 11 prevents the plow from moving laterally toward the plowed ground.

Furthermore, in this connection attention is called to the illustration in Figure 9, in which the furrow indicated by the symbol A indicates the one that has just been completed and the furrow indicated by the symbol B indicates the one last previously made, the latter extends somewhat farther than the furrow A and the land turned over by the plow at the end of the furrow A fills up the adjacent portion of the furrow B. Hence, when the movement of the plow is reversed and power is applied to the wheel 130

12 in a direction tending to move it ahead of the wheel 11, this wheel 12 will ride upon the land in the furrow B that was thrown out of the furrow A by the plow just before its lateral movement from the furrow B into the furrow A, so that there will be no difficulty in causing the wheel 12 to ride over the land side of the furrow at this point.

It is obvious, therefore, that when the plow is moved in either direction, the wheel 12 will be slightly in advance of the wheel 11, and will, therefore, have a slight tendency to travel toward the land side but may be steered by the land side of the furrow in which it is traveling in a straight line. When the engine is reversed at either end of the field, the wheel 12 will advance a short distance independently of the wheel 11, and hence will move transversely relative to the furrow and out of one furrow into the furrow last made, and in doing this, it will ride over some of the land last removed from the last made furrow, and thrown into the next to the last made furrow, and then when the wheel 12 strikes the land side of the last made furrow, the plow will be directed thereby to travel in a straight line parallel with the land side.

In this connection attention is called to another characteristic feature of our improvement, whereby one plow is automatically and forcibly moved out of the ground and the other plow automatically and forcibly moved into the ground, and there held when the engine is reversed at the end of the field. The traction wheels are driven through the gear 16 by means of the small planetary pinion 17 which is driven from the engine. When the plow is in the position shown in Figure 1, the direction of rotation of the small planetary pinion 17 tends to cause the small pinion 17 to travel downwardly and around the pinion 16. However, the plow itself limits the downward movement but this tendency keeps the plow to the left, as shown in Figure 1, forcibly held down into the ground and the plow to the right forcibly held up. When, however, the rotation of the pinion 17 is reversed at the end of the field, then the small pinion 17 will tend to rise upwardly and around the large pinion 16, so that there will be applied to the beam to the left, as shown in Figure 3, a tendency to move upwardly, as indicated by the arrows in Figure 3, and this movement will be continued, as shown by the arrow in Figure 4, until the plow at the right, as shown in Figures 3, 4 and 5, will move downwardly into the ground where its further movement will be limited by the plow engaging the bottom of the furrow. By this means the plow is always held firmly in the furrow and at the end of the field the device is tilted so that one plow moves out of the ground and the other plow into the ground.

If for any reason the plow should at any time move to position with the wheel 12 out of the furrow, except for the short travel when reversing at the end of the field, then it is desirable to stop the engine, and for this purpose we have provided the following mechanism:

Mounted upon the main frame 32 are two downwardly extending arms 44, in which is mounted a shaft 45. Pivotally supported on this shaft 45 is a bell crank lever 46 having one end extended downwardly and supporting a ground wheel 47. The other end extends upwardly and rotatably supports a pinion 48. This pinion 48 is formed with a weight 49 at one side. Fixed to the axle 10 is a small pinion 50.

Mounted on the main frame is an electric switch device indicated generally by the numeral 51, and included in the circuit 52 which supplies current to the spark plugs of the engine. This switch device also includes a lever 53 which is extended to position adjacent to one face of the pinion 48 in position to be engaged by the weight 49.

The operation of this part of the device is as follows:

When the wheel 12 is in a furrow and the wheel 11 is running on the unplowed land, then the wheel 47 will also run upon the land and maintain a certain predetermined elevation with relation to the main axle. When, however, the wheel 12 rides out of the furrow, then the ground wheel 47 will move downwardly away from the main axle a short distance by gravity. This movement, as clearly illustrated by dotted lines in Figure 8, will cause the pinion 48 to be moved into mesh with the pinion 50 on the axle 10, and this will cause a rotation of the pinion 48. When this pinion 48 has moved through approximately a half circle, the weight 49 will then strike the switch lever 53 and open the switch, thus cutting off the circuit of electricity that supplies the spark plug of the engine. When the pinion 48 is not in engagement with the pinion 50, the weight 49 holds the pinion 48 in the position shown by solid lines in Figure 8.

When the wheel 12 is out of the furrow, the plow may advance a certain predetermined distance before the engine is stopped by cutting off the electric current. When the plow is reversing at either end of the field, and the wheel 12 moves from one furrow to another, the distance of this lateral movement of the plow will be less than the amount of distance of travel required for moving the weight 49 to position for operating the switch lever 53. Hence, the engine is not stopped by this device during its reversing movement at the end of the field, but it is only when during the normal travel of the plow across the field, the plow should be moved out of the furrow for any reason,

it will travel only a comparatively short distance when the engine is automatically stopped.

We have also provided means whereby when the plowing has been completed across a field to a fence or other obstruction in the field at the side thereof toward which the plow is advancing laterally, as follows:

Mounted upon the engine is a plate 54 preferably formed with a notch 55, as shown in Figure 10. Pivoted above this plate is a lever 56 having mounted thereon a spring actuated pawl 57 designed to enter said notch. This lever 56 extends laterally to a considerable distance beyond the side of the plow, as shown in Figure 6. It has at its end an arm 58 which normally engages an electric contact device 59 included in the spark circuit of the engine. Hence when this lever 56 is in the position shown in Figure 9, the spark circuit is completed through the arm 58 and the contact point 59, but when the lever 56 is moved in either direction from its position as shown in Figure 9, then the contact between the arm 58 and the contact point 59 is broken. Hence, when the outer end of the lever 56 strikes a side fence or any obstruction placed in the field for that purpose, it will be moved to position for interrupting the spark circuit of the engine.

In practical use and when it is desired to plow a field, the engine is started and the plow is manually guided across the field to form the first furrow, or a furrow may be formed across the field in any desired manner to serve as a guide. After the first furrow is formed, then the device will automatically continue to plow parallel furrows across the field. At the end of each furrow, the direction of travel of the driving wheels will be automatically reversed, and the plow will be moved laterally into the last made furrow, one plow will be drawn out of the ground and the other plow will be moved into the ground.

If at any time during the progress of the plow, it should move out of the furrow, the ground wheel 47 will be lowered by gravity with relation to the main axle and the spark circuit of the engine will be interrupted, thus stopping the engine. When the plowing of the field has been completed up to a side fence or other obstruction, the spark circuit will also be automatically interrupted and the engine stopped.

We claim as our invention:—

1. In a device of the class described, the combination of a frame, a driving wheel for the frame, a prime mover carried by the frame, a beam carried by the frame, two plows on opposite ends of said beam extended in opposite directions and so arranged that as the device is advancing in either direction one of the plows will be in its operative position and the other will be carried

in an elevated position, means for actuating the driving wheel by power from the prime mover, said means being so arranged and combined that when the prime mover is operating to advance the device in one direction it will tend to hold one of the plows down and the other up and when advancing in the opposite direction will tend to hold the plows in their opposite positions, a reversing device extended in both directions from the frame and designed to engage a stationary object in the path of the frame, and means operated by said reversing device upon engaging an object for reversing the movement of the prime mover.

2. In a device of the class described, the combination of a frame, a driving wheel for the frame, a prime mover carried by the frame, a beam carried by the frame, two plows on opposite ends of said beam extended in opposite directions and so arranged that as the device is advancing in either direction one of the plows will be in its operative position and the other will be carried in an elevated position, means for actuating the driving wheel by power from the prime mover, said means including a gear wheel fixed to the driving wheel, a pinion driven by the prime mover and in mesh with said gear wheel, said parts being

so arranged that when the device is moved in either direction the planetary action of the pinion upon the gear wheel will tend to force one plow downwardly and the other upwardly, said means being so arranged and combined that when the prime mover is operating to advance the device in one direction it will tend to hold one of the plows down and the other up and when advancing in the opposite direction will tend to hold the plows in their opposite positions, a reversing device extended in both directions from the frame and designed to engage a stationary object in the path of the frame, and means operated by said reversing device upon engaging an object for reversing the movement of the prime mover.

3. In a device of the class described, the combination of a frame, a driving axle, two driving wheels thereon, a prime mover for rotating the axle, a reversing mechanism between the prime mover and the axle, one of said driving wheels having a limited freely rotatable movement with relation to the axle, a reversing device connected to the reversing mechanism and extended forwardly and rearwardly of the frame.

4. In a device of the class described, the combination of a frame, a driving axle, two driving wheels thereon, a prime mover for rotating the axle, a reversing mechanism between the prime mover and the axle, one of said driving wheels being rotatably mounted on the axle and having two spaced apart shoulders thereon, and a lug

fixed to the axle and designed to engage one or the other of said lugs, a reversing device connected to the reversing mechanism and extended forwardly and rearwardly of the frame.

5. In a device of the class described, the combination of a frame, supporting wheels for the frame designed to travel in and be guided by a previously formed furrow in 10 the ground, a prime mover carried thereby, means for advancing the frame by power from the prime mover, a plow device carried by the frame, means for reversing the direction of advance of the frame, a 15 reverse control mechanism carried by the frame and projected in both directions beyond the frame to engage a stationary object in the path of the frame, and means actuated upon a reversal of the frame driving mechanism for steering the frame laterally on a line slightly divergent from the previously made furrow.

6. In a device of the class described, the combination of a frame, supporting wheels 20 for the frame designed to travel in and be guided by a previously formed furrow in the ground, a prime mover carried thereby, means for advancing the frame by power from the prime mover, a plow device carried by the frame, means for reversing the direction of advance of the frame, a reverse control mechanism carried by the frame and projected in both directions beyond the frame to engage a stationary object in the path of the frame, and means 25 actuated upon a reversal of the frame driving mechanism for positively steering the frame laterally on a line slightly divergent from the previously made furrow for a limited distance only and then automatically discontinuing the positive steering.

7. In a device of the class described, the combination of a driving wheel on the frame, a prime mover carried by the frame, 30 means for rotating the driving wheel by power from the prime mover, a reversing mechanism between the prime mover and the driving wheel, a rod slidably supported by the frame and extended in both di-

rections beyond the frame to engage a stationary object in the path of the device, a lever connected with said rod, and capable of being moved when the rod strikes a stationary object, means connected with said lever for actuating the reversing mechanism when the rod is moved, and a spring for normally holding said lever at either limit of movement past a dead center.

8. In a device of the class described, the combination of a frame, a furrow wheel 60 and a land wheel for supporting and driving the frame, a prime mover carried by the frame and operatively connected with the said wheels, a switch actuating wheel carried by the frame and designed to advance with the frame in position adjacent to the said furrow wheel, and a switch device operatively connected with the switch operating wheel and with the prime mover for operating said switch to stop the prime 65 mover when the switch operating wheel is lowered relative to the furrow wheel as when the furrow wheel moves out of the furrow.

9. In a device of the class described, the combination of a frame, two supporting wheels for the frame, one of which is designed to travel in a furrow, a prime mover on the frame operatively connected with said wheels and capable of being stopped 70 by the breaking of an electric circuit, an electric switch device capable of stopping the prime mover when opened, a bell crank lever, a switch operating wheel carried thereby and capable of engaging the land 75 adjacent to the furrow wheel, a pinion carried by the other end of the lever, a weight carried by said pinion and so positioned as to engage said switch device when the pinion has been moved through a predetermined segment, and a pinion driven by 80 the prime mover and capable of meshing with the pinion on the lever when the switch operating wheel moves downwardly with relation to the furrow wheel.
